TRAVELING BAG

Application filed January 10, 1931. Serial No. 507,954.

This invention relates to improvements in traveling bags and the like, and it consists of the constructions, combinations and arrangements herein described and claimed.

5 An object of the invention is to provide a rest for a partition usually found in traveling bags of the Gladstone type, this rest being produced by modifying one or all of the locking devices of the bag to the extent of forming 50
10 the casing of the locking device with an outstanding flange with which the front edge of the partition is engageable to prevent its sagging.

A further object of the invention is to provide 15 the casing of a locking device with an outstanding flange for the purpose of forming a rest.

Other objects and advantages will appear in the following specification, reference being had to the accompanying drawing in 20 which

Figure 1 is a plan view of a portion of a traveling bag, particularly showing how the partition is supported by the rests that form 25 part of the casings of the locking devices.

Figure 2 is a similar plan view omitting the partition.

Figure 3 is a cross section taken on the line 3—3 of Figure 1.

30 Figure 4 is a cross section of the traveling bag illustrating the general manner in which the partition is supported by one of the rests.

Figure 5 is a fractional perspective view again showing the relationship of the partition 35 to the rests.

Figure 6 is a detail plan view of a modified form of the rest.

A specific application of the invention is to a traveling bag of the Gladstone type, but 40 this is not to be construed as a limitation because the principle of so forming the casing of a locking device as to provide a rest for some movable part of a traveler's appurtenance may be embodied in any type of such appurtenance. Reverting to the example

herein adopted, it is the purpose of the rest generally denoted 1 in all of its forms, to support the front edge 2 of a partition 3 so that the latter will not sag either under the weight of its contents or during the act of securing 50 it to a ledge 4 that is customarily found extending around the front and sides near the top of one section of a Gladstone bag 5.

This bag has several locking devices 6, 7. The device 6 is a key operated lock. The details of this lock are immaterial, it being sufficient to say that the element 8 (Figs. 1 and 2) comprises a spring-pressed projection which contains the barrel of a lock. Upon the insertion and proper turning of a key the locking mechanism can be released so that a subsequent inward pressure on the element 8 will enable lifting the companion section 9 (Fig. 4) away for the opening of the bag. 60

The lateral devices 7 comprise temporary locks by means of which the section 9 may also be held in the closed position. These locking devices 7 are situated near the ends of the bag, and especially serve in holding the section 9 down uniformly to prevent bulging when the bag is rather heavily loaded. 65

In every instance the casing 10 of the locking device is provided with an outstanding flange that provides the rest already denoted 1. The middle rest, additionally denoted 11 because of its distinguishing shape, is extended along the ledge 4 sufficiently far to support approximately one half the length of the partition 3. Ordinarily the front support of the partition 3 is confined to the places where the two curved parts 12 meet the ledge 4. These curved parts occur by virtue of shaping the partition out at 13 to avoid the customary locking devices. 70

With the support of the partition so restricted, the fault of sagging of the partition has become objectionable in bags of this type. By so making the casing 10 of the locking device as to provide an integral out- 80

standing flange, the front edge 2 of the partition will be afforded an ample rest that will prevent any tendency toward sagging.

There is some room for variation both in the shape of the rest flanges 1 and in the places where they shall be located. For instance, the rest flanges may be made smaller as denoted at 14 in Figure 6. Here, as in all other instances, the rest flange is put to use in receiving securing means 15 by which attachment is made to the ledge 4. Should it be desired to omit the rather extensive middle rest flange 11 (Fig. 2) and possibly also the restricted rest flange 14 (Fig. 6), the support 15 of the partition 3 may be confined to the rest flanges 1 of the remaining locking devices 7.

Gladstone bags are usually provided with a snap fastener arrangement at the front to secure the partition 3 when let down (Fig. 1). 10 Such fasteners are now omitted, and the middle rest flange 11 is employed as a mount for turn buttons 16 such as customarily used in securing automobile side curtains. The partition 3 is provided with openings 17 (Fig. 25) 5) near the front edge into which the turn buttons 16 are projectible and then turned.

The operation is readily understood. The partition 3 comprises a hinged flap that can be swung over so as to close the section 5 of the bag (Fig. 4) and keep the contents separate from other portions of the bag. When this partition is swung over the turn buttons 16 (Fig. 5) will fit the openings 17 near the front edge 2 of the partition. The buttons 16 are then turned so as to secure the partition.

These turn buttons are carried by the middle extended rest flange 11 that comprises part of the casing 10 of the locking device 6. 40 The front edge 2 is also supported by minor rest flanges of the casings 10 of the locking devices 7. The arrangement prevents the sagging of the partition 3.

While the construction and arrangement 45 of the improved traveling bag is that of a generally preferred form, obviously modifications and changes may be made without departing from the spirit of the invention or the scope of the claims.

50 I claim:

1. A Gladstone or like traveling bag including an open body portion and a ledge inside of said body portion, said body portion having middle and lateral locking devices 55 on its front wall, a partition permanently hinged to the rear wall of the body portion, said partition being cut out centrally and laterally along its front side to avoid said locking devices, middle and lateral rests supplementing the ledge, being attached to the ledge and extending inwardly of the body portion at the location of said cutaway portions to sustain the partition at said cutaway 60 portions, the middle rest being approximately half the length of the partition, said partition

having a pair of openings, and fastening means carried by the middle rest near its ends to be near the lateral rests, said fastening means entering said openings and being operable to simultaneously clamp the partition down on the middle and lateral rests. 70

2. In a traveling bag having a body portion and a movable partition in the body portion, a cover locking device including a casing secured to a part of the body portion, and a rest member for the partition being integral with and extending from said casing. 75
